UNITED STATES PATENT OFFICE.

FELIX E. VOORHIES, OF DALLAS, TEXAS.

COTTON-SEED LINTER.

1,308,823.

Specification of Letters Patent.

Patented July 8, 1919.

Application filed December 6, 1917. Serial No. 205,848.

To all whom it may concern:

Be it known that I, FELIX E. VOORHIES, a citizen of the United States, residing at Dallas, county of Dallas, and State of Texas, have invented certain new and useful Improvements in Cotton-Seed Linters, of which the following is a specification.

This invention relates to a new and useful form of cotton seed linter for use in linting or removing the lint and fiber from the cotton seed.

A purpose of the invention is to provide an efficiently operating machine which may be used in and about oil mills or other places where cotton seed is reduced to commercial products. A further purpose of the invention is to provide a form of linting machine comprising coöperating linters consisting of carding surfaces arranged to act upon the seed. A still further object of the invention is to provide effective means for collecting and extracting the lint from the seed after said seed has passed through the linting devices.

With the above and other objects in view the invention has relation to a certain combination and arrangement of parts, an example of which is given in the following specification, pointed out in the appended claims and illustrated in the accompanying drawings; wherein,

Figure 1 illustrates a vertical sectional view of the casing of the machine, showing the carding and linting device in elevation.

Fig. 2 illustrates an end view of the machine.

Fig. 3 is a sectional view taken through the rim of the carding device.

Referring now more in particular to the drawings, wherein the same parts throughout are designated by identical reference characters, the numeral 1 indicates the casing of the machine, which casing will preferably be constructed of sheet metal or other suitable material. Within the casing is journaled a pair of rotary carding wheels 2 and 3. The upper carding wheel will preferably be of a little less diameter than the lower one, but any variation of the design and speed of the rotary carding wheels is optional with the manufacturer.

Each carding wheel is mounted upon a shaft 4, ball bearings 5 being used to reduce the friction of the high speed parts to a minimum. Each carding wheel is provided with a plurality of carding points or teeth 6

thickly studded in great numbers on the periphery of the wheels. The carding points 6 are confined to a canvas or other suitable form of rim 7 which is in turn made secure upon the rim 8 of the wheel.

Adjustably stationary carding devices 9, formed on the same arc as the circumference of the rotary carders, are mounted in coöperative relation with the rotary carders and confined in a working position by screw-threaded members 10 being secured to the carders 9 through a bracket 11 which permits of the spacing adjustment of one carding member from the other. Screw-threaded nuts 12, confined upon the screw-threaded member 10 and lying contiguous upon either side of a beam 13, permit the adjustment of the member 9 in a more closely or farther spaced relation with the carding wheels. Either extremity of the member 9 may be adjusted independently of the other end thereof or both adjusted to the same degree of coöperative relation such that the teeth 14 of the stationary carder are brought into a contiguous relation with the revolving teeth 6 of the rotary carder. The carding wheels 2 and 3 are arranged one above the other and are identical in design and construction being companion linters designed to efficiently remove the lint from the cotton seed.

The casing is provided with a cotton seed receiving hopper 15 which is fitted with an angular deflecting plate 16 capable of keeping the seed concentrated at the point of entrance into the carding members.

An air opening 17 is provided in the upper portion of the casing. A discharge spout 18 is fitted in the lower portion of the machine for the purpose of conveying the seed from the linter.

A centrifugal exhausting fan 19 capable of displacing the required volume of air is correlated with the machine, and provided with fan blades 20. A pulley 21 is adapted to drive the fan through a belt 22 driven from a pulley 23 fixed upon the shaft 4 of the linting machine. The lower linter wheel and its shaft 4^a has fixed thereupon a pulley 25 adapted to receive any suitable application of power through a belt or other suitable form of drive. A chain 26 is carried upon sprockets 27 fixed to the shaft 4 for the purpose of driving the two linting wheels from the pulley 25.

The centrifugal exhausting fan is pro-

vided with suction tubes 28, 29, 30 and 31 which connect with the two main air conduits 32, which has direct connection with the centrifugal blower and exhausts from 5 said blower through the discharge pipe 33.

In the operation of this cotton seed linting machine the carding wheels will be driven in a direction indicated by the arrows. Cotton seed will be fed into the receiving hopper 10 per 15 where they will be gradually picked up by the linting carding teeth and carried through the mass of a great number of carding points presented to the seed from the two members 9 and 2. As the rotary carder revolves the seed will be dragged, turned and drawn through the coöperating carders where the carding teeth pull the fiber and lint from the seed. The seed will pass from 15 the wheel 2 and collect in the chamber A of 20 the machine, where a portion of the lint will also collect. The tube 29 through which a high air suction is passed will take up the lint from said chamber and pass it through the discharge pipe 33. A considerable quantity 25 of the lint will adhere to the carding teeth 6 of the wheels and revolve therewith. The suction nozzle or pipe 28 is closely related to the teeth of the wheel such that the lint is drawn therefrom as the teeth pass 30 by the opening of said tube. The seed are concentrated down the baffle plate forming the chamber A and fed into the lower carding wheel and carding plate 9 where they are subjected to the same carding and linting 35 action as above described. The seed thoroughly linted and polished collect in the tube 18 where they are conveyed from the machine. The air suction tube 31 draws the surplus lint from the tube 18 as the seed 40 pass the open extremity of the tube. The lint adhering to the carding teeth of the lower wheel will be removed therefrom by the high suction draft set up through the suction tube 30.

45 The plurality of suction nozzles are disposed at points of vantage about the carding wheels such that the lint is thoroughly removed from the seed leaving a very high grade seed thoroughly polished and linted.

50 This machine collects and saves lint in great quantities from cotton seed to be linted, and is capable of economical use designed to save the mill operator in the operation of linting seed prior to the use of same for the several 55 commercial products to be milled from cotton seed.

The invention is presented to include all such changes and modifications in design and form as may come within the scope of the following claims. 60

Claims:

1. In a seed linting machine of the character described, the combination with a casing provided with a feed opening and discharge spout, a plurality of revolving linters comprising wheels fitted with carder points, said wheels being journaled within the casing, a plurality of semi-circular carder plates fitted with points corresponding to the first mentioned points, said carder plates arranged in an engaging relation to the revolving linters, 70 adjustable screws fitted to the carder plates for varying the proximity of engagement of said plates with said revolving linters, suction tubes arranged to take off the lint, and driving means employed for operating the machine. 75

2. A cotton linter machine comprising a casing, rotary linter devices mounted in the casing, and driving means for same, suction 80 conduits arranged at the periphery of the linter devices, and suction conduits branching off from the first named conduits and arranged beneath the linter devices.

3. A linter machine comprising a casing, 85 an air exhauster means, rotary linters mounted in the casing, and driving means for the linters, substantially large conduits connecting with the air exhauster and terminating in the casing in the horizontal 90 plane of the axis of the rotary linters, and conduits branching off from the named conduits and terminating within the casing just beneath the linters, said last named conduits being of smaller cross sectional area 95 than the first named conduits.

4. A linter machine comprising a casing, a pair of rotary linter cylinders journaled therein one being arranged beneath the other, and driving means, air exhauster 100 means, conduits leading from said exhauster means and connecting with the casing for collecting the lint off the linter cylinders, branch conduits opening at a point near and beneath the linter cylinders, a discharge spout positioned beneath the lower delinter cylinder and connecting with one of the branch conduits. 105

In testimony whereof I hereunto set my hand this the 15th day of Nov., A. D. 1917. 110

FELIX E. VOORHIES.
